UNITED STATES PATENT OFFICE.

FRANK P. KOBERT, OF NEW HAVEN, CONNECTICUT.

ELECTRIC RIVETING APPARATUS.

1,096,921.

Specification of Letters Patent. Patented May 19, 1914.

Application filed July 15, 1913. Serial No. 779,088.

To all whom it may concern:

Be it known that I, FRANK P. KOBERT, a citizen of the United States, and residing at New Haven, in the county of New Haven and State of Connecticut, have invented certain new and useful Improvements in Electric Riveting Apparatus, of which the following is a specification, such as will enable those skilled in the art to which it appertains to make and use the same.

This invention relates to electric riveting, welding and similar apparatus, and the object thereof is to provide an improved device or apparatus of this class which is simple and reliable in operation and comparatively inexpensive; a further object being to provide an improved device or apparatus of the class specified which involves in its construction an ordinary die or punch press, and which is particularly designed for use in riveting or securing attaching staples or yoke-shaped devices in the thimble-shaped heads of strain insulators, but which may be used for other purposes when desired.

The invention is fully disclosed in the following specification of which the accompanying drawings form a part in which the separate parts of my improvement are designated by suitable reference characters in each of the views, and in which;

Figure 1 is a side view of an ordinary die or punch press provided with my improvement, the main or old parts of the press being indicated in dotted lines;—Fig. 2 a front view thereof;—Fig. 3 a plan view of a die bed which I employ showing parts of my improved device or apparatus connected therewith, parts of the construction being in section;—Fig. 4 a view similar to Fig. 3 but showing the parts in a different position;—Fig. 5 a cross section on the line 5—5 of Fig. 3;—Fig. 6 a perspective view of an electrode which I employ;—Fig. 7 a section on the line 7—7 of Fig. 5, and;—Fig. 8 a section on the line 8—8 of Fig. 7.

In the drawing forming part of this specification, reference being particularly made to Figs. 1 and 2, I have indicated at a , in dotted or broken lines, an ordinary die or punch press provided with the usual bed plates a^2 , and in the practice of my invention I connect with one side of the framework of the press, a bracket b the top of which is flush with the top of the bed plate a^2 , and on which is mounted an electric transformer c with which is connected circuit wires c^2

and c^3 which may be connected with any suitable source of electrical supply. I also mount on the bed plate a^2 a die bed d which is of the same general form as the bed plate and in the top of which is a transverse space d^2 in which are mounted two dies or die jaws d^3 and d^4 which are movable transversely of the press and the ends of which are connected with the die bed by a tongue and groove construction as shown at d^5 .

The end portion d^6 of the die bed, adjacent to the transformer c is formed independently of the rest of said die bed, and is connected therewith by side plates b^7 , and said end portion d^6 of the die bed is insulated from the remaining part thereof, as shown at d^8 .

Pivoted to the inner side of the end portion of the die bed d opposite the insulated portion d^6 , and as shown at d^9 is a lever arm e which extends forwardly and transversely of the die bed, and mounted in said end portion of the die bed is a transverse cross head e^2 similar in form to the dies d^3 and d^4 and provided with a central vertical pin e^3 which passes through a central slot e^4 in the lever arm e , and by moving the lever arm e in opposite directions, the cross head e^2 may be correspondingly moved transversely of the press and in the die bed d .

Connected with the opposite end portions of the cross head e^2 are rods f which pass through the die d^4 and into and secured in the die d^3 and mounted on said rods f are spiral springs f^2 which bear on the die d^4 and on collars f^3 secured to said rod.

The die bed d , or the insulated end portion thereof is provided with stops g to limit the outward movement of the die d^3 , and the body of the die bed is provided adjacent to the insulated end portion with similar stops g^2 which limit the outward movement of the die d^4 , and said die d^4 is provided with projecting end members g^3 which operate in connection with the stops g^2 , and the body portion of the die bed is also provided centrally thereof with stops g^4 which operate as stops for both of the dies d^3 — d^4 in their movement to the right, or inward movement.

The stops g^2 consist of pins which pass vertically through the sides of the die bed and through the bed plate a^2 of the parts, as clearly shown in Figs. 2 and 5; and the lower ends of said pins are connected by a cross head g^5 between which and the bed plate a^2 of the parts are placed springs g^6 , and con-

nected centrally with the cross head g^5 is a rod g^7 with the lower end of which is connected a foot lever g^8 which is pivoted in the back bottom portion of the press frame at g^9 , and the front end portion of which projects forwardly and is adapted to serve as a treadle.

Mounted in the central top portion a^3 of the press frame is the usual vertically movable punch or die plunger h , and at one side of the part a^3 of the press frame I secure a keeper i in which is mounted a vertically movable plunger rod i^2 with the upper end of which is connected a lever i^3 which is pivoted to the press frame i^4 , the connection between the lever i^3 and the plunger rod i being made by a pin i^5 passed through the upper end of the plunger rod and through the slot in said lever, and connected with the lever i^3 is a spring i^6 secured to the press frame at i^7 , which normally holds said lever and said plunger rod in a raised position, the depressed position of said parts being shown in Figs. 1 and 2.

25 Pivottally connected with the lower end of the plunger rod i^2 is an electrode block j having a plate extension j^2 which projects in the direction of the transformer c and with which is also connected a spring, copper 30 per conductor k which is also connected with said transformer, and a similar conductor k^2 is connected with said transformer and with the die bed d , or the end d^6 thereof.

As hereinbefore stated, my improved riveting apparatus is particularly designed for use in securing, attaching, volkes or staples in the thimble-shaped heads of strain insulators, and in Figs. 1 and 5, I have shown at m one of said thimble-shaped heads, and at 40 n one of said yokes or staples.

The dies d^3 and d^4 are provided in their adjacent faces with grooves or recesses o adapted to receive the yoke or staple n , and the normal position of the parts connected 45 with the die bed d is that shown in Fig. 4. In the operation of this device, the yoke or staple n is dropped into position between the dies d^3 and d^4 , when in the position shown in Fig. 4, and the thimble-shaped 50 cap or head m is placed on said dies, as shown in Figs. 1 and 5, with the sides of the yoke or staple n extending up through the corresponding holes in the bottom of said thimble-shaped head. The foot lever g^8 is then depressed which withdraws the stops g^2 so that the die d^4 may be forced back into connection with the die d^3 , as shown in Fig. 3, by the springs f^2 . The lever i^3 is then depressed and this forces the 55 electrode block j into connection with the ends of the arms or side portions of the staple or yoke n , as shown in Fig. 1, and this operation completes the circuit through the conductors k and k^2 and through said 60 electrode, and through the end portion d^6

of the die bed d , and through the dies d^3 and d^4 , and the ends of the sides of the staple or yoke n within the cap m are highly heated. The lever i^3 is then raised and the lever arm manipulated to draw the dies d^3 and d^4 into the position shown in dotted lines in Fig. 3, and indicated in Fig. 5, in which position the cap m and the sides of the staple or yoke n will be directly under the punch or die plunger h , and at this time, the press is manipulated in the usual manner to force said punch or die plunger downwardly, and the ends of the sides of the staple or yoke n are riveted in the cap m , as will be readily understood.

80 In the bottom of the die bed d is a water chamber p and connected with the opposite end portions thereof are water supply and discharge pipes p^2 and p^3 , and by means of this construction, the said die bed may be 85 kept cool, or approximately so, during the operation of the apparatus, by causing a constant circulation of water through the chamber p .

Although I have shown and described my 90 invention as designed for a particular purpose, it will be understood that the said invention is not limited in use to any particular purpose, and changes in and modifications of the construction herein described 95 may be made, within the scope of the appended claims, without departing from the spirit of my invention or sacrificing its advantages.

Having fully described my invention what 100 I claim as new and desire to secure by Letters Patent is:—

1. In an apparatus of the class described, a frame provided with a horizontal transverse die bed, die jaws movable toward and from each other and transversely of the die bed and of the frame, means for operating said die jaws, an electrical transformer mounted at one side of the frame, a vertically movable die plunger mounted in the 105 frame centrally of and above the die bed, another vertically movable plunger mounted between the die plunger and the transformer and provided at its lower end with an electrode, and means for passing an electric current through the transformer, the electrode and the die jaws.

2. In an apparatus of the class described, a punch press frame, a die bed mounted transversely thereof, die jaws mounted in 120 the top of said bed and movable toward and from each other and transversely of said die bed and of the frame, and means for operating said jaws, said die bed being also provided at the sides thereof with stops to limit 125 the movement of the die jaws and two of which are vertically movable, an electric transformer mounted at the side of the press frame, said press frame being also provided with a vertically movable die plunger, an- 130

other plunger mounted between the die plunger and the transformer, and provided at its lower end with an electrode, and means for passing an electric current through said transformer, through the electrode and through the die jaws.

3. In an apparatus of the class described, a frame provided with a horizontal die bed one end portion of which is insulated, two die jaws mounted thereon and movable toward and from each other and transversely of the die bed, means for limiting the movement of said jaws in opposite directions, and means for operating said jaws.

15 4. In an apparatus of the class described, a frame provided with a horizontal die bed one end portion of which is insulated, two die jaws mounted thereon and movable toward and from each other and transversely of the die bed, means for limiting the movement of said jaws in opposite directions, and means for operating said jaws, said frame being also provided above the die bed with a vertically movable die plunger and at one side thereof with an electrical transformer, and between the die plunger and the transformer with a supplemental vertically movable plunger provided at its lower end with an electrode.

20 5. In an apparatus of the class described, a frame provided with a transverse horizontal insulated die bed, one end portion of said die bed being insulated from the other, die jaws mounted on said die bed and movable transversely thereof and transversely of the frame, said frame being also provided centrally of and above the die bed with a die plunger, and at one side of which is a sup-

plemental plunger provided at its lower end with an electrode.

6. In an apparatus of the class described, a frame provided with a horizontal die bed and above said die bed with a die plunger, and at one side of which is a supplemental plunger provided at its lower end with a pivoted electrode, and die jaws mounted on the die bed and movable toward and from each other and transversely of the die bed and of the frame.

7. In an apparatus of the class described, a frame provided with a transverse die bed centrally of and above which is a vertically movable die plunger at one side of which is a supplemental plunger, said die bed being also provided with die jaws movable transversely thereof and of the frame and toward and from each other, and means for passing an electric current through a work piece held between said die jaws.

8. A machine of the class described provided with a die bed, work piece holders mounted on said die bed and movable transversely thereof, a vertically movable die plunger mounted above said die bed, and means for passing an electric current through a work piece held by said work piece holders.

In testimony that I claim the foregoing as my invention I have signed my name in presence of the subscribing witnesses this 14th day of July, 1913.

FRANK P. KOBERT.
